UNITED STATES PATENT OFFICE.

EDWARD KUMKE, OF NEW YORK, N. Y.

DESIGN FOR TRIMMING.

SPECIFICATION forming part of Design No. 16,252, dated September 15, 1885.

Application filed July 6, 1885. Term of patent 7 years.

To all whom it may concern:

Be it known that I, EDWARD KUMKE, of the city, county, and State of New York, have invented a new Design for Trimming, of which the following is a full, clear, and exact description.

Reference is to be had to the accompanying drawing, forming a part of this specification, in which the figure shows a front view of my newly-designed trimming.

The leading feature of my design consists in the representation of a depending net-work ornamented by double connected balls at the juncture of the strands; also, in the ornamentation of the lower edge of the net-work by a row of balls having conical stems presenting the appearance of spirally-wound strands.

In the drawings, D represents the band, from which depends the net-work C, ornament-

ed on its lower edge with balls A, having conical stems α , presenting the appearance of spirally-wound strands, and the net-work is also ornamented between its edges at the juncture of its strands by double connected balls.

Having thus described my invention, what I claim as new, and desire to secure by Letters Patent, is—

The design for trimming herein shown and described, the same consisting in the depending net-work C, ornamented between its longitudinal edges at the juncture of its strands by the double connected balls B, and on its lower edge by balls A, having stems α .

EDWARD KUMKE.
